UNITED STATES PATENT OFFICE.

NICHOLAS WITSCH, OF JERSEY CITY, NEW JERSEY, ASSIGNOR TO THE AMERICAN LITHOGRAPHIC COMPANY, OF NEW YORK, N. Y.

DESIGN FOR AN ORNAMENTATION FOR BOXES.

SPECIFICATION forming part of Design No. 28,910, dated June 21, 1898.

Application filed May 4, 1898. Serial No. 679,737. Term of patent 7 years.

To all whom it may concern:

Be it known that I, NICHOLAS WITSCH, a citizen of the United States, residing at Jersey City, in the county of Hudson and State 5 of New Jersey, have invented and produced a new and original Design for the Ornamentation of Boxes, of which the following is a specification, reference being had to the accompanying drawing, forming a part thereof.

10 My design is intended for the ornamentation of boxes.

In the accompanying drawing the design is shown on the lid or cover of a box, the view being a front elevation with the lid raised.

15 The design comprises a panel framed in by

a border A. Within the border and surrounding the panel is an endless irregularly looped or curved ribbon B.

C denotes an endless lacework within the border, surrounding the panel and forming a 20 background for the ribbon.

I claim—

The design for the ornamentation of boxes substantially as shown and described.

In testimony whereof I affix my signature 25 in presence of two witnesses.

NICHOLAS WITSCH.
